UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

CASTING AND CONTROLLING MECHANISM OF TYPE-BAR-CASTING MACHINES.

1,085,891.

Specification of Letters Patent.

Patented Feb. 3, 1914.

Application filed October 6, 1911. Serial No. 653,128.

To all whom it may concern:

Be it known that I, HEINRICH DEGENER, a subject of the German Emperor, residing at 26 Hollmannstrasse, Berlin, in the German Empire, have invented new and useful Improvements in the Casting and Controlling Mechanism of Type-Bar-Casting Machines, of which the following is a specification.

- 10 The present invention consists in improvements in the casting and controlling mechanism of type bar casting machines, and is particularly applicable to machines made and sold under the trade mark "Linotype".
15 The mold carrier of such a machine is a wheel loose on a fixed axis and rotatable in a vertical plane through its cycle of movement by a pinion driven by the driving mechanism of the machine. A clutch is 20 combined with the said mechanism which can be opened to stop the machine at the end of each cycle. The molds on the carrier differ from each other in size but this invention concerns itself only with differences 25 in body. They are arranged around the carrier at equal distances from each other, parallel with diameters of the carrier and at a common radial distance from the axis of the latter. Four is the usual number of 30 molds on a carrier. When the latter is in the casting position, it holds the top mold in the casting position and all the others out of it for the time being. But there is a hand clutch operatively positioned be- 35 tween the pinion above mentioned and the carrier, by which the pinion is disengaged from the driving mechanism in order that the carrier may be turned through the angle necessary to put another mold in the casting 40 position. When there are four molds on a carrier, this angle will be 90° or a multiple of it and the pinion is of such a size that one rotation of it turns the carrier through 90°. After each type bar has been cast it 45 is ejected between a pair of knives parallel with each other and supposed to be held apart by a distance exactly equal to the "body" dimension, in order that the type bar may be trimmed down over each side to 50 bring it to that dimension. One of these knives is stationary—the other is adjustable up to and away from it. They and the means for so adjusting the movable knife constitute the adjustable trimming mecha- 55 nism of the machine. Obviously, a change

of mold for "body" must be accompanied by a readjustment of the trimming mechanism in order that the latter may be set for the same "body" as that of the mold then in casting position. This condition of the 60 trimming mechanism is hereafter referred to as being "in proper adjustment".

The invention comprises automatic means by which a mold or the mold carrier or the adjustable mechanism for trimming the 65 sides of the type bars, controls the driving mechanism of the machine so that the latter shall be stopped whenever a mold or the mold carrier is moved into operative position at a time when the trimming mecha- 70 nism is not in adjustment with the particular mold to be used.

The accompanying drawings illustrate a preferred constructional form of the invention as applied to such a machine as has 75 just been described, but the details may be modified without getting outside the scope of the invention.

Figure 1 is a front elevation of the improved means for effecting a change of 80 mold: Fig. 2, a transverse section on the line 2—2 of Fig. 1: Fig. 3, a horizontal section on the line 3—3 of Figs. 1 and 2: Fig. 4, a rear elevation of a detail: Fig. 5, a sectional side elevation of the driving pinion 85 for the mold carrier: Fig. 6, a front elevation of the automatic means for controlling the driving mechanism; and Fig. 7, a sectional plan of part of it.

1 is the mold carrier; 2, 2, its molds; 3, 90 its driving pinion loose on the shaft 4 which is turned four times in each cycle by the driving mechanism; 5, the clutch fast on the shaft 4 to hold the pinion 3 to the latter; 6, the clutching pin; 7, its socket in the pin- 95 ion 3; 8, the introducing groove; 9, the re-engaging spring resilient between a shoul- 100 der 10 on the boss 11 and a shoulder 12 fast to the shaft 4; 13, the stationary knife; 14, the adjustable one; 15, 15, a pair of set 105 screws alined with the adjusting movement of the knife 14, working in fixed lugs 16, 16, and bearing against steps 17 on one side of a plate 18 adjustable at right angles to the said movement and having its opposite side 110 in constant contact with the outside of the said knife 14; 19, a pin working in a so called vise frame 20 and normally present- ing its nose beyond the rear face of the lat- ter; 21, a link operatively connected with 110

the clutch of the driving mechanism of the machine (which clutch and mechanism are not included in the figures) and 22, a lever fulcrumed on the vise frame 20 and having 5 its arms in contact with the front ends of the pin 19 and link 21 respectively. Only two sets of steps 17 are shown in Fig. 6 to prevent crowding. The motion of the link 10 21 to the rear stops the driving mechanism of the machine and the reversal of it starts the said mechanism. All the foregoing parts are substantially as heretofore.

Referring to Figs. 1 to 5, 23 is a hand crank fast on the front end of a shaft 24 15 rotatable in a bracket 25 fast to the machine frame. 26 is a collar fast on the shaft 24 and having a cam surface 27 operative in the vertical plane. 28 is an arm pivoted on the bracket 25 and provided with two 20 fingers 29, 30, carrying rollers. The finger 29 engages in an annular groove 31 in the periphery of the boss 11 and the finger 30 with the cam surface 27 with which it is kept in contact by the spring 9. 32 is a 25 spur wheel loose upon the shaft 24 and in gear with the pinion 3. It has more teeth than the latter, the excess quantity being a whole number which is also an aliquot part of the quantity of teeth on the pinion 3. 30 Thus, if the latter has 24 teeth, the wheel 32 may have an excess quantity of four *i. e.*, of one sixth—28 in all. There is a clutch between the shaft 24 and the wheel 32 consisting of a pin wheel 33 fast on the said wheel 35 and having a pin 34 for each aliquot part of the number of teeth in the wheel 32, the respective aliquot part (4 teeth) or a total of seven pins (Fig. 4), each pin being positioned after the respective aliquot part (4 teeth). 35 is a clutching finger fast on a slide 36 working in a slot 36^a in the collar 26 parallel with the axis of the latter and having the same radius as the pins 34. The presence of the finger 30 in the recess of the 40 cam surface 27, keeps the finger 35 out of engagement with the pin wheel 33, against the resilience of a spring 37.

The operation of the parts is as follows: A rotation of the hand crank 23 in the direction of the arrow in Fig. 1, makes the right-hand rise of the cam surface 27 (Fig. 3—if the arm 28 is pivoted on the right hand of the collar 26, but in the opposite direction, if that arm is pivoted on the left-hand) 35 swing the arm 28 to the front far enough to disengage the pinion 3 from the clutching pin 5 and, therefore, from the driving mechanism of the machine, against the resilience of the spring 9, while the spring 37 pulls 40 the finger 35 into engagement with the next pin (Fig. 4) on the pin wheel 33 thereby locking the wheel 32 to the said crank. The completion of the rotation of the latter, turns the pinion 3 through one rotation, 45 bringing its socket 7 opposite the pin 6 and

the cam surface 27 opposite the finger 30, whereupon the spring 9 reengages the pinion 3 with the driving mechanism of the machine and also the finger 30 in the recess in the cam surface 27, making the said finger disengage the finger 35 from the pin wheel 33.

Referring to Figs. 6 and 7, 38 is a link connecting the plate 18 to one arm of a bell crank lever 39 fulcrumed on the vise frame 20 and having the other arm connected to an interponent 40 sliding in a suitable guide, and 41 a projection upon a mold or upon the mold carrier, the arrangement being such that when the adjustable knife 14 has not been adjusted for the same “body” as the mold 2 then in use, the knife 14 holds the interponent 40 operatively between the projection 41 and the pin 19, so that the movement of the mold in use or of the mold carrier into its operative position (which expression is to include either the casting or the trimming position thereof) makes the projection 41 engage the interponent and through it the pin 19, thereby pushing them both to the front (Fig. 7) and rocking the lever 22 so as to push the link 21 to the rear. If, on the other hand, the knife 14 has been adjusted, the interponent 40 will be out of the path of the projection 41 and the link 21 will not be pushed to the rear. When there are only two molds 2 on the carrier 1, two sets of steps on the plate 18, one projection 41, and two positions for the interponent 40 suffice. If there are more molds, the 50 number of sets of steps must be increased, which will increase the number of positions for the interponent and require more projections 41 positioned to engage with the respective positions of the interponent.

Having described my invention, I declare that what I claim and desire to secure by Letters Patent is:—

1. In mechanism of the type described comprising adjustable trimming mechanism, the combination with the mold carrier and the driving mechanism of the machine, of means for controlling the said driving mechanism actuated by the mold carrier when it is moved into its operative position at a time 110 when the trimming mechanism is not in proper adjustment.

2. In mechanism of the type described comprising adjustable trimming mechanism, the combination with a mold carrier, a plurality of molds thereon, and the driving mechanism of the machine, of means for controlling the said driving mechanism actuated by the mold carrier when it is moved into its operative position at a time when the trimming mechanism is not in proper adjustment.

3. In mechanism of the type described, the combination with the adjustable trimming mechanism and the driving mechanism of 130

- the machine, of means for controlling the said driving mechanism actuated by the said trimming mechanism when the latter is not in proper adjustment.
5. In mechanism of the type described, the combination with the mold carrier, the adjustable trimming mechanism and the driving mechanism of the machine, of means for controlling the said driving mechanism connected to the said trimming mechanism and actuated by the mold carrier when it is moved into its operative position at a time when the trimming mechanism is not in proper adjustment.
10. In mechanism of the type described, the combination with a mold carrier, a plurality of molds thereon, the adjustable trimming mechanism, and the driving mechanism of the machine, of means for controlling the said driving mechanism connected to the said trimming mechanism and actuated by the mold carrier when it is moved into its operative position at a time when the said trimming mechanism is not in proper adjustment.
15. In mechanism of the type described, the combination with a mold carrier, a plurality of molds thereon, the adjustable trimming mechanism, and the driving mechanism of the machine, of means for controlling the said driving mechanism connected to the said trimming mechanism and actuated by the mold carrier when it is moved into its operative position at a time when the said trimming mechanism is not in proper adjustment.
20. In mechanism of the type described, the combination with a mold carrier, a plurality of molds thereon, the adjustable trimming mechanism, and the driving mechanism of the machine, of means for controlling the said driving mechanism connected to the said trimming mechanism and actuated by the mold carrier when it is moved into its operative position at a time when the said trimming mechanism is not in proper adjustment.
25. In mechanism of the type described, the combination with a mold carrier, a plurality of molds thereon, the adjustable trimming mechanism, and the driving mechanism of the machine, of means for controlling the said driving mechanism connected to the said trimming mechanism and actuated by the mold carrier when it is moved into its operative position at a time when the said trimming mechanism is not in proper adjustment.
30. In mechanism of the type described, the combination with a mold carrier, a plurality of molds thereon, the adjustable trimming mechanism, and the driving mechanism of the machine, of means for controlling the said driving mechanism connected to the said trimming mechanism and actuated by the mold carrier when it is moved into its operative position at a time when the said trimming mechanism is not in proper adjustment.
35. In mechanism of the type described, the combination of trimming mechanism adjustable to correspond to different sizes of type bodies, driving mechanism, and automatic means for throwing the driving mechanism out of action when the trimming mechanism is in improper adjustment.
40. In mechanism of the type described, the combination of the adjustable trimming mechanism, the driving mechanism, and means whereby the driving mechanism is
- controlled by the trimming mechanism according to the adjustment of the latter.
9. In mechanism of the type described, the combination of the movable mold carrier, the adjustable trimming mechanism, the driving mechanism, and means controlled by the adjustment of the trimming mechanism whereby the movement of the mold carrier to operative position controls the driving mechanism.
10. In mechanism of the type described, the combination with the mold carrier, the adjustable trimming mechanism, and the driving mechanism of the machine, of an interponent connected to the said trimming mechanism and operatively held by it between the said mold carrier and the said driving mechanism at a time when the said trimming mechanism is not in proper adjustment when the mold carrier is moved into its operative position.
11. In mechanism of the type described, the combination with a mold carrier, a plurality of molds thereon, the adjustable trimming mechanism, and the driving mechanism of the machine, of an interponent connected to the said trimming mechanism and operatively held by it between the mold carrier and the said driving mechanism at a time when the said trimming mechanism is not in proper adjustment when the said mold carrier is moved into its operative position.
12. In mechanism of the type described, the combination of adjustable trimming mechanism, means for bringing a mold into operative relation thereto, and means to arrest the machine when the trimming mechanism is not adjusted to correspond to the mold.
- In witness whereof I have hereunto set my hand in the presence of two witnesses.
